[57] CLAIM

The ornamental design for a planing tool, as shown and described.

DESCRIPTION

FIG. 1 is a front perspective view of the planing tool, taken from above and one side, showing my new design; FIG. 2 is a rear perspective view taken from below and the opposite side thereof;

FIG. 3 is a side elevational view thereof, the opposite side being substantially identical;

FIG. 4 is a top plan view thereof; and

FIG. 5 is a front elevational view thereof.

FIG. 1.

FIG. 2.

FIG. 3.

FIG. 4.

FIG. 5.
